UNITED STATES PATENT OFFICE.

WILLIAM HENRY SUMBLING, OF TORONTO, ONTARIO, CANADA.

RECTIFYING-MACHINE FOR SHELLS.

1,308,125.

Specification of Letters Patent.

Patented July 1, 1919.

Application filed June 8, 1918. Serial No. 238,954.

To all whom it may concern:

Be it known that I, WILLIAM HENRY SUMBLING, a subject of the King of Great Britain, of the city of Toronto, county of York, 5 Province of Ontario, Canada, have invented certain new and useful Improvements in Rectifying-Machines for Shells, of which the following is a specification.

My invention relates to improvements in 10 rectifying machines for shells, and one of the objects of my invention is to design a machine whereby the internal bottom of the forging will be smoothed out before the forging goes to the boring lathe so as to prevent loss of time and material through 15 breakage of the cutters and head carrying the same, belonging to the boring-lathe. Another object of my invention is to utilize certain of the parts of my machine to rectify 20 the internal bottom of the shell after it has been bored, but before the same has been nosed, so as to remove any roughness in the bottom.

In the following specification, I shall describe 25 my machine in its preferred embodiment and in the claims shall set forth the parts I claim as new.

Figure 1 is a plan of my machine showing 30 a horizontal longitudinal central section through the major parts thereof, as well as through a forging mounted in place. Fig. 2 is a side elevation of one end of the machine showing the particular means for locking or holding the forging in place, which is shown 35 in dotted position. Fig. 3 is a vertical cross section through the base of the machine on the line 3—3, Fig. 1, showing, in elevation, the vise for clamping the forging firmly in place, and Fig. 4 is a horizontal longitudinal 40 section through one end of the supporting means for the spindle, showing the preferred construction therefor.

In the drawings, like characters of reference refer to the same parts.

It is well-known that shell-forgings are often made with the inner end of the bore 45 very irregularly formed, and the result is that when the forging is operated upon by the cutters in a boring-lathe, very often the 50 cutters and the head supporting the same are absolutely ruined. The modern boring lathes used in boring shell-forgings run at high speed, and they are invariably automatic in their action, and, therefore, the cutters 55 very frequently jam in the irregularities in the inner end of the bore, even though

the machinist is giving careful attention to his work, with the result that these cutters are badly damaged, and sometimes the shell forging is ruined. It is the object of my invention to clean away all such irregularities in the inner end of the bore in the forging before the same is operated upon by the boring lathe, thus not only greatly reducing cost of maintenance of boring lathes, but 60 also reducing to a minimum the danger of damaging the shell-forging. My rectifying machine, though very strongly built, does not cost as much to manufacture as a boring lathe, and the preliminary work to 65 be done thereby is very quickly and accurately performed.

A is the base of the machine, and carried thereby are two standards B and C in which is journaled the spindle D. This spindle is 70 provided with any suitable cutter-head E carrying suitable cutters F. Supported by the standard C is a sleeve G which projects beyond one side thereof. The longitudinal axis of said sleeve is alined with the longitudinal axis of the spindle D so that this spindle will pass therethrough, and have bearing therein after any suitable manner as shown at 2 and 3. This sleeve G is preferably provided with a flange 4 through 80 which passes bolts 5 whereby the same is secured to the standard C through the medium of nuts 6 screwing on said bolts. To give additional support to the sleeve in the said standard, the sleeve projects 85 through said standard as shown at 7 and is firmly held therein. Of course, any other suitable means may be employed to support the said sleeve from said standard.

8 is an internally-threaded nut, suitably 90 fixed in the standard B, and operating through this nut is an externally-threaded sleeve 9, the outer end of which is provided with suitable manipulating means such as a hand-wheel 10 keyed thereto. 11 is a collar 100 carried by the outer end of the spindle 9 with which the manipulating means 10 contacts to withdraw the spindle. As shown in Fig. 1, the spindle D passes through the sleeve 9, and although this spindle is shown 105 as tubular in form, it may be made solid.

A suitable vise is carried by the base A to clamp the forging 12 firmly in place to prevent rotary movement thereof. This forging is placed over the sleeve G as shown 110 clearly in Fig. 1 and in order to place it in the preferred form of clamping means,

which is in the form of a vise, the upper member or jaw 13 (which is pivoted to the lower jaw 14 carried by the base A by a bolt or equivalent means 15) is uncoupled from said lower jaw and thrown upwardly around the bolt 15. After the forging has been placed in the jaw 14, the jaw 13 is closed and locked in place. The preferred locking means for this vise comprises a bolt 16 pivoted by a pin 17 in the flange 18 of the jaw 14. The flange 19, as well as the flange 18, is provided with a slot 20 to permit the necessary movement of the bolt 16. The nut 21 co-acts with the threaded end of the bolt 16 to lock the jaws 13 and 14 together.

As the forging 12 is placed on the sleeve G, it is moved until its tapered bore comes into contact with the head 22 of the sleeve G.

To absolutely lock the forging 12 against longitudinal displacement during the operation of the cutter F, a threaded locking-bar 23 is mounted in the plate 24 of a bracket 25 which is pivoted at 26 to the base A. This locking-bar is provided with a hand-wheel 27, or equivalent means, to manipulate the same. It will be observed that the longitudinal axis of the bar 23 is in alinement with the longitudinal axis of the forging 12 and consequently with the spindle D, when it occupies the position shown in Figs. 1 and 2. The bracket 25 permits the bar 23 to be swung sidewise out of the path of movement of the forging 12 when the same is being placed and removed.

The inner end of the head 22 is rounded or beveled as shown at 28, and this fact, together with the further fact that the head 22 is preferably hardened, prevents damage to the sleeve G. The inner end of the sleeve G is preferably reduced in external diameter so as to form a flange 30 over which the head 22 passes, and it is through this flange and head 22 that the fastening means such as a pin 29 is passed. The external diameter 45 of the head 22 is substantially the same as the external diameter of the sleeve G, which is less than the diameter of the bore of the shell-forging 12.

In the construction of means shown and described for supporting the cutter-head E, it will be observed that this cutter-head is journaled within the head 22. When the manipulating means 10 is operated to withdraw the spindle D to provide for a fresh operation, the necessary longitudinal movement of the cutter-head E is provided for by the space α separating this head from the flange 30.

Any suitable means may be used to drive the spindle D: The preferred means comprises a pulley b mounted on a shaft c journaled in bearings in the standards B and C. d is a pinion keyed to the shaft D with which is constantly in mesh the gear-wheel e keyed to the spindle D. The pinion d has

a considerably wider face than the face of the gear-wheel e, so that these two wheels may be constantly in mesh notwithstanding the longitudinal reciprocating movement of the said spindle D.

It will be observed that by reason of the sleeve G, the spindle D is given proper support to prevent any other than longitudinal and rotary movement of the cutter-head E and its cutters.

To insure the absolute holding of the forging 12 in the vise or clamping means used, I provide the jaws 13 and 14 each with a pair of steel blocks f, serrated on their inner edges, and which project beyond the inner face of these jaws.

By providing the manipulating means 10 or its equivalent, the operator has a very sensitive way of controlling the longitudinal movement of the spindle D and cutters F so that he will not jam his cutters and so break them.

In order to increase the sensitiveness of the means for controlling the feed-spindle D, I prefer to provide an ordinary type of thrust ball-bearing g positioned between the flange h of the sleeve 9 and the shoulder i of the spindle D. This thrust ball-bearing will prevent the binding between the spindle D and the sleeve 9 when the cutters F are in operation, which binding would have a tendency to feed the cutters automatically forward with more or less injurious results. The use of the thrust ball-bearing or its equivalent adds to the sensitiveness of the feed with beneficial results.

It will be observed upon referring to Fig. 3 particularly that the blocks f solely contact with the inner end of the forging 12 so that the forging will be positively held against axial movement when firmly clamped between the jaws 13 and 14.

As will be understood, the longitudinal axis of the spindle D passes through the center of the space or opening between the jaws 13 and 14, and since the blocks f project an equal distance beyond the jaws 13 and 14, and further from the fact that as the forging 12 is placed on the sleeve G, when its tapered bore contacts with the head 22, the longitudinal axis of the said forging will be held in alinement with the longitudinal axis of the spindle D.

As before mentioned, one of the objects of my invention is to utilize my machine to rectify any roughness in the bottom of the shell before nosing. In order to do this, it is not necessary to utilize the locking-bar 23 nor its supporting bracket, nor is it necessary to use the thrust ball-bearing before described, or its equivalent.

Claims:

1. A shell-rectifying machine comprising a pair of standards spaced apart; means for rotatably holding the boring-bar in said

standards comprising means in the rear standard for feeding the bar forward, and an elongated bushing located at the forward standard and carried thereby at one end, 5 the other end projecting into the bore of the work operated upon and supporting the boring-bar near its point of operation on the work, and means for clamping the work in position on the machine.

10 2. A shell-rectifying machine comprising a pair of standards spaced apart; means for rotatably holding the boring-bar in said standards comprising means in the rear

standard for feeding the bar forward, and an elongated bushing located at the forward 15 standard and carried thereby at one end, the other end projecting into the bore of the work operated upon and supporting the boring-bar near its point of operation on the work; means carried by the machine and positioned near its forward standard to clamp the work against turning, and means pivoted to the machine, and whereby the work is clamped against longitudinal displacement.

WILLIAM HENRY SUMBLING.
